The ornamental design for a foldable game table, as shown and described.

DESCRIPTION

FIG. 1 is a perspective view of the foldable game table.
FIG. 2 is a top view thereof.

FIG. 3 is a bottom view thereof.

FIG. 4 is a right-side view thereof.

FIG. 5 is a left-side view thereof.

FIG. 6 is a front view thereof.

FIG. 7 is a rear view thereof; and,

FIG. 8 is a perspective view of the foldable game table in a folded position.
The broken lines shown in the figures are for the purpose of illustrating the folding game table and form no part of the claimed design.
